3 Claims. (Cl. 202—221)

My invention relates to an oven for distilling in general solid material in small fragments which coagulates relatively little at high temperatures for the purpose of extracting from it products such as oil, gas and tar which are produced in the course of the distillation.

This oven is designed particularly for the distillation of schists, shales and bituminous sandstones which either do not coagulate at all or do so only slightly.

The oven making the subject matter of the invention is designed with a view to realising the following conditions which are necessary to obtain the maximum yield of oil under the best conditions:

1. The schist or shale must be heated progressively and rapidly to a predetermined temperature which must never be exceeded and which must be able to be regulated with considerable accuracy. This temperature varies, according to the material to be treated, between 450° centigrade and 650° centigrade.

2. To obtain a rapid heating the schist or shale must be heated in a condition in which it is loosely packed and must be subjected to internal movements.

3. The volatile products given off which are different at the different temperatures reached by the material in the course of its distillation must be led off as soon as formed so as to withdraw them from the effects of prolonged heating.

4. All the volatile products must be mixed and supplemented with superheated steam before being withdrawn and cooled.

5. In the case of certain sulphurous schists or shales it is desirable to collect separately the products, such as carbon dioxide and sulphurated hydrogen which are given off at low temperatures so as to avoid their coming into contact with the oil bearing products. The sulphur content of these oils will thus be diminished.

6. It is important to avoid any entry of air into the distillation chambers in order to avoid oxidising the volatile products.

This oven is designed also with a view to realising a large capacity for production per square meter of ground space, to be easy to operate, economical in upkeep and to require relatively little heat.

The attached drawings represent an embodiment of the oven.

Fig. 1 is a vertical section through the axis of the oven.

Fig. 2 is a plan view taken at the level A—B.

Fig. 3 is a horizontal section along the line C—D.

Fig. 4 is a vertical section through one of the central tubes of each chamber on an enlarged scale.

The oven possesses for example eight vertical distillation chambers I which are identical and which are disposed in a circular fashion about a vertical axis of symmetry.

These chambers are formed by a column of individual distillation chambers of refractory material provided with large connecting joints.

The inner wall of each individual distillation chamber possesses a portion which increases in diameter towards the bottom above which is arranged a portion considerably less in height which opens towards the top the walls being inclined at an angle of about 45°.

The average interior diameter of each individual distillation chamber may be for example 30 centimetres the height being also 30 centimetres. The height of a column of these individual distillation chambers may be for example about 6 meters.

The eight distillation columns are surmounted by eight vertical cast pipes 2 whose upper openings are fixed to a cylindrical reservoir 3 into which penetrates a feeding screw 4 which delivers the schist or shale into the centre of this reservoir where it forms a heap which overflows into each of the tubes 2.

Eight flaps 5 whose inclination can be adjusted enable the feeding of each pipe 2 to be controlled and suppressed as required.

The schist or shale may be broken up so as to contain lumps for example of from 1 to 40 millimetres in diameter.

It may be desirable to charge the oven with a somewhat damped schist or shale so as to increase the quantity of superheated steam which mixes with the volatile products.

The distillation chambers are heated by a plurality of series of eight gas burners 6 arranged symmetrically. The air necessary for the combustion is taken in by apertures of adjustable cross section giving access to the burners.

The hot gases produced by each burner are divided into two currents which circulate successively around every individual chamber of a column. They finally circulate around the tubes 2 before escaping through two symmetrical apertures 7 into two chimneys.

The eight columns of distillation chambers are mounted on a metal plate 8 pierced by eight corresponding holes. Under this plate is fixed a

funnel-shaped hopper 9 for receiving the waste schist or shale.

This hopper whose lower extremity dips into water forming a hydraulic joint debouches on to a rotating floor 10 provided with two scoops 11 for removing the used material.

Each distillation chamber is traversed by a central tube 12 which is given a rotary motion. These tubes are pierced by a large number of holes 13 and on the outside are provided with a helical shelf 14.

These tubes have two functions:

(a) They permit the material to descend regularly on account of the helical shelf which breaks the arch-like agglomerations of the schist or shale which are continually forming. These arch-like agglomerations come to rest upon the interior surfaces of the distillation chambers where these are widening towards the top. Their effect is to prevent the material passing through the chambers from becoming jammed which would cause considerable friction on the rotating central tube and would also have the undesirable effect of preventing internal movements within the material.

Thanks to the continual formation and breaking down of these arch-like agglomerations important movements are produced in the mass of the material both in the direction from the periphery of the chambers towards the centre and from the centre towards the periphery which movements facilitate the heating of the material.

In order to counteract the tendency of the schist or shale to descend more rapidly in the central region than in the peripheral region of the distillation chambers the helical shelf 14 is arranged in such fashion that the rotation of the central tube tends to screw down the tube into the material. As the tube cannot be driven down through the material the descent of the latter will be retarded in the central region so that the average velocity with which the schist or shale descends through the distillation chambers is approximately the same at the periphery as at the centre.

(b) The tubes also serve for collecting the volatile matter given off by the schist or shale which penetrates into the tubes through the holes which are provided.

The gas which is given off at low temperatures such as carbon dioxide and sulphuretted hydrogen on the one hand, and on the other hand the volatile matter given off at higher temperatures may be collected separately.

To this end a piston 15 connected to a rod fixed to a covering member closing the upper opening of the central tube separates the two sorts of products.

The low temperature gases traverse the tube through the holes situated above the piston. When they reach the upper part of the tube they pass out through holes provided in this region and pass into the reservoirs 3 from which they are drawn off by a tube 16.

The products formed at higher temperatures pass into the tube through the holes situated below the piston and descend through the tube whose lower opening is associated with the stem portion of a fixed in-take cone 17. They pass out through the tube 18.

The piston 15 may be displaced in the tube so as to vary the region of separation of the two products. It is very important to withdraw the volatile products in the downward direction. If

these products should rise in the tube, since the temperature of the latter diminishes from bottom to top the volatile material through rising would reach a region of the tube which is at a lower temperature than their temperature of condensation. The vapours would condense there and would trickle down the tube where they would be vaporised again, the cycle being repeated until these volatile products were destroyed.

The exhausted schist or shale coming into contact with the water which forms the hydraulic joint vaporises a considerable quantity.

This vapour becomes superheated in contact with the hot material in the hopper 9. It is taken in through the cones 17 where it mixes with the products of distillation.

All the useful products of the distillation are accordingly mixed in the hot state with superheated steam—a condition necessary for obtaining the maximum yield from oil shales.

The water vapour traversing the exhaust material in the hopper also has the effect of extracting the last traces of volatile material which the treated shale still contains. It will be noted that the arrangements for collecting the volatile products, for introducing fresh material and for withdrawing the exhaust material efficiently prevent any air gaining access to the distillation chambers.

Actually it is in the lower region of the chambers in the neighbourhood of the intake tubes that the pressure is lowest. Now on account of the hydraulic joint which is provided at the bottom of the outlet hopper no entry of air is possible in this region.

In the upper portion of the tubes above the pistons the pressure may approximate to that of the atmosphere so that there will not be any passage of air across the schist or shale contained in the feeding screw nor across the joints occurring at the place where the central tubes pass out of the reservoir 3.

The maximum temperature of the distillation chambers may be regulated with considerable accuracy by adjusting the cocks of the burners and by consulting the indications of the pyrometers 19 whose leads penetrate into the lower portion of the central tubes.

What I claim is:

1. In an apparatus for the heat treatment of shales, schists, sandstones and the like for the extraction of volatile products, a hollow vertical distillation column comprising a plurality of superposed distillation chambers, each chamber having a lower portion with a cross-section gradually increasing towards the base and an upper portion of smaller height with a cross-section increasing towards the top of the chamber, a rotatable central tube extending vertically through said distillation column, means for rotating said central tube in one direction, projecting elements disposed on the outer surface of said rotating tube and spaced from the inner wall of the column, said elements being adapted to retard the descent of the material in the central portion of the column and to prevent arch-like agglomerations of the material from packing upon rotation of said tube, the latter being provided with holes through which the volatile products given off from the material can be withdrawn.

2. In an apparatus for the heat treatment of shales, schists, sandstones and the like for the extraction of volatile products a hollow vertical distillation column comprising a plurality of

superposed distillation chambers, each chamber having a lower portion with a cross section gradually increasing towards the base and an upper portion of smaller height with a cross section increasing towards the top of the chamber, a rotatable central tube extending vertically through said distillation column and provided on its outer surface with a helical shelf having its outer edge spaced from the inner wall of the column and means for rotating said tube and helical shelf in a direction to retard the descent of the material in the central portion of the column and to prevent arch-like agglomerations of the material from packing or jamming, the central tube being pierced with holes through which the volatile products given off from the material are withdrawn from said column in a vertical direction.

3. In an apparatus for the heat treatment of shales, schists, sandstones and the like for the extraction of volatile products, a hollow vertical dis-

tilation column comprising a plurality of superposed distillation chambers, each chamber having a lower portion with a cross section gradually increasing towards the base and an upper portion of smaller height with a cross section increasing towards the top of the chamber, a rotatable central tube extending vertically through said distillation column and provided on its outer surface with a helical shelf having its outer edge spaced from the inner wall of the column means for rotating said tube and helical shelf in a direction to retard the descent of the material in the central portion of the column and to prevent arch-like agglomerations of the material from packing or jamming, the central tube being pierced with holes through which the volatile products given off from the material can be withdrawn from said column in a vertical direction, and a suction pipe communicating with the lower end of said tube.

FRANZ FLORENT RAOUL ANDRÉ GILLES. 20
